Primary Examiner — Deanna L Pratt*Assistant Examiner* — Lilyana Bekic(74) *Attorney, Agent, or Firm* — Cermak Nakajima & McGowan LLP; Tomoko Nakajima(57) **CLAIM**

The ornamental design for a mouthpiece for inhaler, as shown and disclosed.

DESCRIPTION

FIG. 1 is a front elevational view of a mouthpiece for inhaler showing my new design;

FIG. 2 is a top plan view thereof;

FIG. 3 is a right side elevational view thereof;

FIG. 4 is a left side elevational view thereof;

FIG. 5 is a rear elevational view thereof; and

FIG. 6 is a bottom plan view thereof.

FIG. 7 is a front and top perspective view thereof; and,

FIG. 8 is a perspective view thereof in a position of use. The broken line in FIG. 8 is included to show unclaimed environment only and forms no part of the claimed design.
